SHOWER STALL

James F. Fulton, 806 The Crescent, Mamaroneck, N.Y.

Filed June 5, 1963, Ser. No. 75,237

Term of patent 14 years

(Cl. D4—4)

Fig. 5

Fig. 6

FIG. 1 is a front perspective view of a shower stall showing my new design;

FIG. 2 is a cross-sectional view thereof taken on line 2—2 of FIG. 1;

FIG. 3 is a cross-sectional view thereof taken on line 3—3 of FIG. 2;

FIG. 4 is a cross-sectional view thereof taken on line 4—4 of FIG. 2;

FIG. 5 is a side elevational view thereof; and

FIG. 6 is a rear view thereof.

I claim:

The ornamental design for a shower stall, substantially as shown.
